APPARATUS FOR BENDING TUBING

Harry C. Jennings, Jr., Los Angeles, Calif.

Application June 21, 1952, Serial No. 294,787

1 Claim. (Cl. 153—40)

1

This invention relates to an apparatus for bending tubing.

In the construction of wheel chairs, certain types of porch furniture, and similar articles, the frame is formed of sections of seamless metal tubing. This tubing is frequently bent to provide elements of the frame. For example, a leg of a wheel chair may have its upper end bent at approximately right angles thereto to provide an armrest. There are a number of other situations where it is desirable or necessary to bend the tubing at various angles, frequently at right angles.

When ordinary cylindrical tubing, such as is used in wheel chairs, porch furniture and the like, is bent severely the outer side of the tubing is stretched and the inner side of the tubing is greatly compressed even though the tubing is bent around the end of a mandrel that is inserted therein. The compression on the inner side of the tubing is such as to produce a plurality of transversely extending wrinkles or corrugations. These corrugations produce a roughened surface on the inner side of the bend which is objectionable for a number of reasons including that of unsightliness.

An object of the present invention is to provide an apparatus for bending tubing wherein the wall of the tubing at the inner side of the bend is longitudinally indented in the course of the bending operation. By indenting the tubing wall in this manner the objectionable transverse corrugations are avoided and in lieu thereof a relatively short narrow longitudinal indentation is formed at the inner side of the bend which is normally in a position so that it is concealed or not readily observable.

With the foregoing and other objects in view, which will be made manifest in the following detailed description and specifically pointed out in the appended claim, reference is had to the accompanying drawings for an illustrative embodiment of the invention, wherein:

Figure 1 is a top plan view of a portion of a bending apparatus embodying the present invention, parts being broken away and shown in horizontal section and illustrating a section of tubing as having been mounted thereon preparatory to being bent;

Fig. 2 is a view similar to Fig. 1 but illustrating the bend as having been completed;

Fig. 3 is a horizontal section taken substantially upon the line 3—3 upon Fig. 2;

Fig. 4 is a view similar to Fig. 2 but illustrating the tubing as being in the process of being bent;

2

Fig. 5 is a horizontal section taken substantially upon the line 5—5 upon Fig. 4 in the direction indicated; and

Fig. 6 is a perspective view of a portion of bent tubing which has been bent in accordance with the present invention.

Referring to the accompanying drawings wherein similar reference characters designate similar parts throughout, the major portion of 10 the bending apparatus disclosed conforms to one form of tubing bending apparatus that is now in general use. Consequently all details thereof have not been illustrated. Essentially the apparatus disclosed consists of a mandrel 10 on which a section of seamless metal tubing T is adapted to be telescoped. This mandrel is usually mounted on a limber rod arranged axially of its end which holds the mandrel against longitudinal or axial displacement but enables lateral movement to some extent.

On one side of the mandrel there is swingably mounted a jaw 11 which is semi-cylindrically recessed, as at 12, to accommodate approximately one-half of the cylindrical tubing. This jaw is swingably mounted for swinging movement about a pivot provided by a vertical shaft 13. This pivot may be forcibly rotated either by power or manually. Attached to the jaw 11 is a semi-circular roll 14 which has a groove 15 extending 20 around its semi-circular periphery and centrally of this groove there is an outwardly projecting rib 16. The end of the mandrel is rounded off, as indicated at 17, and that portion of the mandrel which is adjacent its end and which is opposite the rib 16 is longitudinally grooved as indicated at 18. A movable jaw 19 is mounted on the jaw 11 and is adapted to be tightened toward the jaw 11 by means of a manually operated eccentric 20 so that that portion of the tubing 25 which projects beyond the end of the mandrel 10 may be clamped between the two jaws 19 and 11 and swung thereby about the pivot 13. In so doing the tubing is axially shifted and bent, the bending action taking place about the rounded-off end 17 which is concentrically arranged with respect to the pivot 13. On the opposite side of the mandrel 10 from the roll 14 there is a movable support 21 adapted to be advanced and retracted by means of a manually operated linkage 22. This support has rollers 23 and slidably supports against the rollers a follow block 24. The follow block 24 is grooved to accommodate approximately one-half of the tubing T. When it is desired to bend the tubing the tubing is 30 telescoped onto the mandrel and the jaw 19 tightened toward the jaw 11. The support 21

is also advanced so that it crowds the tubing and the mandrel toward the roll 14. The jaw 11, movable jaw 19 and roll 14 are then swung as a unitary structure about the axis of the vertical shaft 13, thus bending the tubing around the rounded end 17 of the mandrel. As this bending takes place the follow block 24 rolls against the rollers 23 and moves with the tubing from the position shown in Fig. 1, through the position shown in Fig. 4, to the position shown in Fig. 2. As the bending takes place the rib 16 indents or depresses the tubing wall at the inside of the bend into the groove 18 thus producing on the inside of the bend a short narrow indentation indicated at 25 on Fig. 6. As will be noted from an inspection of the drawing, if the roll employed is to bend the tubing through a ninety degree bend, the rib 16 occupies an arc of less than ninety degrees of the roll. The ends of the rib are beveled off, as indicated at 26 and 27, to be tangent to the bottom or back of the groove 15. These beveled portions on the rib enable the tubing to be slipped onto the mandrel, in Fig. 1, without interfering with the rib and after the bending is complete the bevel at 27 is disposed opposite the mandrel, enabling the tubing to be slid off of the mandrel when the bend is completed. In other words, in both extreme positions the rib 16 is disposed wholly outside of the groove 18. But in the intermediate position, shown in Fig. 4, the rib 16 enters the groove 18 producing the depression at 25. This depression extends only along the inside of the bend in the tubing and usually it will be located on the under side of a structural element of a wheel chair, porch furniture or the like. Consequently it is not readily observed. The indenting of the tubing wall at this point enables the bend to be made without the formation of transverse creases or corrugations such as are formed when the tubing is bent without employing the rib 16 or the groove 18. Consequently in side elevation tubing bent in this manner appears to have a smooth continuous bend.

The conventional tube bending apparatus may be readily modified to adapt the present invention by merely grooving the end of the mandrel with a groove 18 and providing a semi-circular roll 14 on which a rib 16 is formed. Usually in the construction of these rolls two half rolls are held in assembled relation and are turned on a lathe so as to form the groove 15

and a continuous rib 16. Thereafter the bevels at 26 and 27 may be formed by grinding off the ends of the rib so that these bevels will be disposed opposite the mandrel at both extreme positions of the roll.

From the above described construction it will be appreciated that a novel method and apparatus is provided for bending tubing wherein by the formation of a narrow longitudinal indentation in the tubing wall at the inside of the bend a smooth bend can be secured, avoiding the formation of transverse corrugations.

Various changes may be made in the details of the construction without departing from the spirit and scope of the invention as defined by the appended claim.

I claim:

A tube bending apparatus comprising a mandrel on which tubing to be bent may be telescoped, a roll rotatably mounted adjacent the end of the mandrel, the end of the mandrel being rounded off with a radius of curvature approximately concentric with the axis of rotation of the roll, means for clamping the tubing against the roll, means for swinging the clamping means and roll about the axis of rotation of the roll, a follow block mounted for movement longitudinally of the mandrel on the opposite side thereof from the roll, there being a circumferentially extending rib extending partially around the roll, the ends of the rib being beveled off approximately tangent to the roll, and there being a groove formed in the mandrel opposite the roll and extending to the rounded end of the mandrel whereby as the roll and clamping means are swung the rib will depress the tubing into the groove over a portion of the interior of the bend in the tubing and the tubing may thereafter be removed from the mandrel by sliding it longitudinally off of the end of the mandrel.
